UNITED STATES PATENT OFFICE

WILLIAM O. C. CARSON, OF FREEMAN, WEST VIRGINIA

MINER'S COMBINATION TAMP AND NEEDLE

Application filed March 20, 1930. Serial No. 437,500.

This invention relates to a combination tamping bar and needle for use in connection with "shooting" coal in the mining thereof.

It is aimed to provide a novel combination 5 of parts which will enable a more rapid and safer method of preparing and filling the holes with explosives.

A particular object is to provide a construction wherein the needle and tamping 10 bar are capable of individual as well as joint use, wherein a novel tamping head is used, wherein such relative movements of the parts in connection with the hole as will produce spark by friction is avoided, and wherein 15 in a novel handle is used in connection with the needle when operated independently of the tamping bar.

Various additional objects and advantages 20 will become apparent from a consideration of the description following taken in connection with accompanying drawings illustrating an operative embodiment.

In said drawings:—

Figure 1 is a view in elevation, partly 25 broken away, illustrating all of the parts assembled,

Figure 2 is a view showing the parts in operative relation for tamping a charge, the latter also being shown,

Figure 3 is a view showing the needle alone 30 in side elevation, and in connection with the charge and having the handle in place,

Figure 4 is a detail sectional view taken on the line 4—4 of Figure 1, and

Figure 5 is a detail sectional view taken on the line 5—5 of Figure 3.

Referring specifically to the drawings, 10 designates the tube or sleeve of any suitable metal which detachably carries at its lower 40 end, a tamping head 11, the latter preferably being of copper and having a socket 12 in the upper end in which the lower end of the sleeve 10 is detachably screw threaded, a lock nut 13 preferably being threaded on the sleeve and abutting the head. It will be noted that the head is substantially conical with its base lowermost. Further, the head is provided with a suitable number of transverse openings 14.

50 Slidably and snugly extending through

bores of the tube 10 and head 11 is a needle 15, preferably of copper, pointed at its lower end as shown and having its upper end square or polygonal in cross section as at 16.

A handle 17 is used when the needle 15 is 55 operated independently of the tamping head and sleeve as will be later described. Screw threaded or otherwise attached to the handle 17 at 18 is a shank 19 which has a socket member 20 at its lower end detachably engaging the squared portion 16 and being interiorly square so as to intimately fit the same. In order to secure the handle detachably to the needle, a latch 21 is employed, the same for instance being made from a single strand of wire with a portion 22 pivoted in an opening in the shank 19 and an end 23 upset to prevent accidental detachment. The other end of the latch 21 is formed into a lug 24 which 60 detachably engages openings 25 and 26 in 65 the portion 16 and socket 20, respectively. 70

In the use of the device with a hole such as 27 suitably drilled in the coal, the needle 15 alone is arranged centrally of the hole and pellets 28 of explosives are threaded 75 onto the needle and fall to the bottom of the hole, or in lieu of the pellets, loose powder or explosive may be applied to the hole with care used to assure central location of the needle. After the explosive is applied, clay or sludge as at 29 is arranged in the hole thereover and thereupon the sleeve 10 and head 11, with the handle 17 and connected 80 parts removed, are slid onto the needle 15 as shown in Figure 2. Thereupon the sleeve 10 is reciprocated and if desired 85 turned at times so as to tightly compress the charge 28 within the hole. After the charge is thus compressed, the sleeve 10 and head 11 are removed and the handle 17 90 is rigidly but detachably connected to the needle. The handle could not be in place during the tamping operation because sufficient movement for the sleeve could not take place. With the handle secured to the needle, the latter may be turned and reciprocated in order to remove the needle and provide the central hole in the explosive. 95

Through the use of the invention, it will 100 be realized that the sleeve and head are

guided by the needle in such manner that the sleeve will not strike the coal during reciprocation and the various parts of the device will not so strike each other as to produce spark by friction or otherwise accidentally fire the charge. The particular shape of the head 11 aids toward this end since the sleeve is much smaller in diameter than the hole. In addition, the openings 14 will accommodate loose or falling coal which will gradually work out of the same and below the same so as to be tamped into place. Since the device holds the tamping bar in the center of the hole there will be no "ravelling" of holes which "ravelling" is a serious objection in present methods. The invention also overcomes "squibbing" and its consequent danger.

Various changes may be resorted to provided they fall within the spirit and scope of the invention.

I claim as my invention:—

1. A device of the class described comprising a needle, and a tamping member 25 slidably mounted thereon and removable therefrom, and a handle detachably applicable to said needle.
2. A device of the class described comprising a needle, a handle applicable thereto, a latch pivoted to one of said parts and both parts having openings adapted to register for engagement by the latch.
3. A device of the class described having a tamping head, said head being substantially conical, and said head having a transverse opening therethrough for the purpose specified.
4. A device of the class described having a tamping head, said head having a transverse opening therethrough for the purpose specified.
5. A device of the class described having a tamping head, a sleeve serving as a handle therefor, said head having a socket, said sleeve being detachably screw threaded in said socket, said head being substantially conical, and a needle along which the head and sleeve are slidable.

In testimony whereof I affix my signature.

WILLIAM O. C. CARSON.
